UNITED STATES PATENT OFFICE.

ALBERT KAGI, OF SYRACUSE, NEW YORK, ASSIGNOR TO THE PROSPERITY COMPANY, INC., OF SYRACUSE, NEW YORK, A CORPORATION OF NEW YORK.

PRESSING ELEMENT FOR PRESSING MACHINES.

Application filed October 12, 1927. Serial No. 225,794.

This invention relates to pressing elements for pressing machines as garment pressing machines and has for its object a particularly simple and efficient valve mechanism for controlling the alternate flow of air and steam to the pressing face of the pressing element.

The invention consists in the novel features and in the combinations and constructions hereinafter set forth and claimed.

In describing this invention, reference is had to the accompanying drawings in which like characters designate corresponding parts in all the views.

Figure 1 is a longitudinal sectional view through a pressing element embodying my invention.

Figure 2 is an enlarged fragmentary sectional view through the valve mechanism.

The pressing element is usually the head of a pressing machine which also includes a buck on which the garment to be pressed is first laid, the head being movable toward and from the buck.

1 designates the head or pressing element which is formed with an internal heating chamber 2 for steam and a lengthwise channel 3 within the steam chamber, but disconnected therefrom, the channel opening 30 through the pressing face of the head 1 through a line of perforations 4. Also, the pressing face is covered with a suitable covering as of wire mesh 5 which serves to distribute the steam over the face of the garment being pressed. A distributing plate 6 is preferably carried by the covering 5 and opposed to the jet openings 4. The channel 3 serves as a conduit through which either steam or air can be projected through the jet openings 4.

The valve for controlling the flow of air and steam as here shown includes a valve casing 7 mounted on the head and having an outlet passage 8 in alignment with a passage 9 in the head which passage extends through a web 10 into the channel 3. The casing is also formed with separated valve chambers 11, 12 both of which open into the inlet chamber 8, these valve chambers being

separated by a partition 13. The upper 50 valve chamber 11 communicates with the source of supply of air through a pipe 14 and the lower valve member 12 communicates through a passage 15 with the steam chamber 2. The flow of steam or air is controlled from the chambers 11 and 12 to the outlet passage 8 by a pair of alternately operable valves having a single handle.

16 designates the valve in the chamber 11, this valve being normally against its seat 60 17 and having a stem 18 extending to the outside of the casing through a suitable packed gland 19. The valve is held against its seat by a spring 20 located in a cap 21 which threads into a suitable opening in 65 the casing. The valve 22 which controls the flow of steam into the passage 8 from the valve chamber 12 also has a stem 23 similar to the stem 18 and arranged parallel thereon and is acted upon by a spring 24 70 arranged similarly to the spring 20. The valves are alternately operated by means of a hand lever 25 pivoted at 26 to a bracket 27 on the valve casing, one arm of the lever coacting with the valve stem 18 and the 75 other arm with the valve stem 23.

Obviously, by moving the hand lever 25 to the left, the stem of the valve 22 will be opened and steam will pass from the steam chamber 2, valve chamber 12, passage 8, 80 channel 3 through the jet openings 4 and when the handle 25 is moved to the right from its normal position, the steam valve 22 will remain closed and the air valve opened to permit air to pass from the pipe 85 14 through the chamber 11, passage 8, channel 3 and the jet openings 4.

What I claim is:

The combination with a pressing element of a pressing machine having an internal 90 chamber for a heating medium and a lengthwise channel having jet openings opening through the pressing face of a pressing element, of a valve comprising a casing mounted on the pressing element and having a 95 passage communicating with said channel, a pair of separated chambers one being connected to the internal steam chamber of the

pressing element and the other having an inlet pipe for compressed air, normally closed spring pressed valve heads in said chambers and having stems extending to the outside of the casing and a lever pivoted to the casing and coacting with said stems on opposite sides of its axis, whereby when the lever is rocked in one direction from

neutral position, one valve is opened and when it is rocked in the other direction, the other valve is opened.

In testimony whereof, I have hereunto signed my name, at Syracuse, in the county of Onondaga and in the State of New York, this 12th day of July, 1927.

ALBERT KAGI.
